UNITED STATES PATENT OFFICE

124,950

DESIGN FOR A COMBINED LIPSTICK AND VANITY CASE

Arthur R. Botham, New York, N. Y.

Application November 29, 1940, Serial No. 96,928

Term of patent 7 years

To all whom it may concern:

Be it known that I, Arthur R. Botham, a citizen of the United States, residing in the city and State of New York, have invented a new, original, and ornamental Design for a Combined Lipstick and Vanity Case, of which the following is a specification, reference being had to the accompanying drawing, forming a part thereof.

In the drawing:

Figure 1 is a top perspective view of a combined lipstick and vanity case showing my new design. Figure 2 is a side view thereof in elevation.

I claim:

The ornamental design for a combined lipstick and vanity case, as shown.

ARTHUR R. BOTHAM.
